UNITED STATES PATENT OFFICE.

WILLIAM S. HOWARD, OF BELLEVILLE, NEW JERSEY, ASSIGNOR, BY MESNE ASSIGNMENTS, TO RUSSELL M. EVERETT, OF BLOOMFIELD, NEW JERSEY.

INTERNAL-COMBUSTION ENGINE.

1,214,922.

Specification of Letters Patent.

Patented Feb. 6, 1917.

Application filed December 23, 1911. Serial No. 667,435.

To all whom it may concern:

Be it known that I, WILLIAM S. HOWARD, a citizen of the United States, residing at Belleville, in the county of Essex and State of New Jersey, have invented certain Improvements in Internal-Combustion Engines, of which the following is a specification.

This invention relates to means for controlling the inlet and exhaust of internal combustion engines, and the object of the invention is in general to provide an improved control which shall be very effective and positive, and yet at the same time simple in construction and operation. More particularly the objects of the invention are to obtain a port opening of maximum capacity; to positively close said port opening when desired; to quickly open or close said port open, to provide for this purpose a port opening extending substantially the length of travel of the piston; to open or close such a port by the piston and other means acting in conjunction therewith; to employ for said other means a rotary valve, and more particularly a sleeve valve; to make the opening or closing of the port depend on the movement of the piston more than upon movement of the sleeve, and thus take advantage of the rapidity of movement of the piston; to obtain an especially large port opening at the end of the intake and at the beginning of the exhaust, so as to completely fill the cylinder and to quickly discharge its contents after explosion; to provide for this purpose a lateral extension of the port opening; to secure an improved drive for the sleeve valve, and to obtain other advantages and results as may be brought out in the following description.

Referring to the accompanying drawings, in which like numerals of reference indicate the same parts throughout the several figures,

Figure 1 is a central sectional view of the cylinder of an engine embodying my invention;

Fig. 2 is a transverse section taken on line A—A of Fig. 1;

Fig. 3 is a section similar to Fig. 1, of

the cylinder of an engine illustrating a modified or split sleeve;

Fig. 4 is a development of the interior of the cylinder, showing the inlet and exhaust ports;

Fig. 5 is a similar development of the sleeve, showing its port;

Fig. 6 is a side elevation of the cylinder portion of an engine of my improved construction, with the crank case broken away to show means for driving or rotating the sleeve; and Fig. 7 is a diagrammatic section illustrating a group of four cylinders having their sleeve gears in series.

In the specific embodiment of the invention shown in said drawings, and referring especially to Figs. 1 and 2, 1 indicates the cylinder of an internal combustion engine, mounted upon the crank case 2 and having within itself a piston 3 connected by a rod 4 to the crank 5 of the shaft 6. Said cylinder is water-jacketed in my suitable and well-known manner, as at 7, and provided at its top with a suitable opening 8 for the spark plug, not shown, while in the sides of the cylinder are inlet and exhaust ports 9 and 10, respectively, elongated lengthwise of the cylinder as will be hereinafter more fully described.

Between the piston 3 and the cylinder 1 is a cylindrical sleeve 11 which extends past the cylinder ports 9 and 10 longitudinally of the cylinder, and at its lower end is provided with means for rotating it continuously in one direction. In the specific form shown in Fig. 1, said sleeve 11 is supported at the lower part of the cylinder 1 between upper and lower ball bearings 12 and 13 and has an outer peripheral gear 14 adapted to be driven by an intermeshing pinion 15 which is shown in Fig. 6. The precise means for transmitting rotary motion to the sleeve 11 is unimportant, however, and I do not restrict myself to the form in which I have shown for purposes of illustration nor to any other particular form. It is necessary only that the sleeve be rotated, continuously in one direction, and preferably without longitudinal movement.

In said sleeve is a port 16 which by the rotation of the sleeve is passed alternately over the inlet and exhaust ports 9 and 10 of the cylinder, said passing bearing a definite relation to the movement of the piston, so that the opening of both intake and exhaust depends not alone upon the rotation of the sleeve, but also upon the movement of the piston. The advantage of this is apparent when it is remembered that the speed of the piston is much greater than the rotary speed of the sleeve can be, and as a matter of fact by thus taking advantage of the movement of the piston in opening the intake and exhaust much larger openings are obtainable than in any other way. The opening of the intake and exhaust is illustrated by Figs. 4 and 5 of the drawings, where the horizontal dotted lines indicate divisions of movement of the piston and the vertical dotted lines indicate divisions of movement of the sleeve, both said divisions being made in the same period of time. When the forward edge 17 of the sleeve port 16 is in coincidence with the rear edge of the cylinder inlet 9, the piston is at the top of its stroke and everything is closed. As the piston moves down one division, the forward edge 17 of the sleeve port advances one division and a portion of the inlet port 9 bounded by the lines 18, 18 is thus opened; as the piston moves down one more line and the edge 17 advances another division, the intake is increased accordingly, and this continues until when the piston top has reached the fifth horizontal line from the top, the sleeve port 16 registers with the cylinder inlet port 9 and all above the piston is open, the piston itself blocking the rest. As the piston continues downward, the rear edge 19 of the sleeve valve begins to pass over the cylinder inlet port 9, so that when the piston is down to the sixth line the inlet port 9 is open for its portion above said sixth line, and to the right hand of the vertical line 20. When the piston reaches the seventh horizontal line, similarly, the port 9 is open for its portion above said line and to the right hand of the vertical line 21. Now, in order to obtain during the downward movement of the piston through the last two divisions and also during its upward movement through the last or bottom division an enlarged intake opening so as to receive the greatest possible amount of gaseous fuel, I provide in the sleeve an extension 22 of the port 16 extending rearward of the rear edge 19 thereof, and it will be noted that as the piston reaches the eighth line, this extension opens for its upper half between the vertical dotted lines 23 and 24, with an extension 25 of the cylinder inlet 9. This gives that much more intake in addition to the portion of the main

port 9 which is to the right hand of the vertical line 23. When the piston reaches the ninth horizontal line, or bottom of its stroke, that portion of the main inlet 9 to the right of the vertical line 26 is open and also the extensions 22 and 25 register between the vertical lines 26 and 27, so that all together there is a very large intake opening. The sleeve port is then in the first dotted position shown in Fig. 5, reading from the left. As the piston starts upward again, the cylinder inlet 9 closes as the piston reaches the eighth horizontal line, by the rear edge 19 of the sleeve port 16 having reached the forward edge 28 of the cylinder inlet 9, and very quickly thereafter the piston closes the extension 22.

This upstroke of the piston compresses the charge which has been taken in, as usual, and when at the top of its movement again, the sleeve port 16 has moved into the second dotted position shown in Fig. 5.

Explosion then takes place and the piston makes its downward stroke, and as said piston approaches the limit of its down-stroke or the ninth horizontal line in Fig. 4, the lower part of the port 16 in the sleeve registers with an extension 29 of the exhaust port 10, so that a considerable exhaust area is opened very quickly. When the piston is at the seventh horizontal line in Fig. 4, the forward edge 17 of the port 16 in the sleeve coincides with the rear edge 30 of the exhaust port 10, and as the piston moves on downward both the exhaust 10 and the extension 29 open. When the piston is down to the eighth line, the exhaust 10 is open to the vertical line 31 and the extension 29 is open for its upper half from the forward end of the sleeve extension 22 to the rear end of the cylinder exhaust tension 29, or approximately between the vertical dotted lines 32 and 33. When the piston is clear down, to the ninth line, the exhaust is open to the vertical line 34, and the extensions 22 and 29 register between the vertical dotted lines 33 and 31, approximately. As the piston starts up on its exhaust stroke, it closes the sleeve extension 22 between the 8th and 7th lines, but the cylinder exhaust 10 is being uncovered more and more by rotation of the sleeve and a large opening is available for the gases to escape. Of course after the piston gets half-way up, the sleeve port 16 begins to pass out of registration with the cylinder port 10, and the available exhaust opening decreases, but it is not until the piston is clear up, to the position where it was at the beginning of our description, that the exhaust is wholly closed by coincidence of the rear edge 19 of the sleeve port with the forward edge 35 of the cylinder exhaust port 10.

It will be noted from Figs. 4 and 5 of the

drawings, just referred to, that the port openings of both the cylinder and rotary valve extend longitudinally a distance substantially or approximately the length of 5 the piston stroke or travel, or in other words they extend from a point as near the cylinder head as possible and yet be sealed by the piston at its innermost or rearward position, outward substantially to the point 10 reached by the inner end of the piston on its outward or forward stroke. This enables not only the burnt gases to escape laterally and directly, but also the fresh charge to enter in the same manner. I believe it to 15 be broadly new to obtain such a port opening, extended approximately the full length of movement of the piston, and I wish to be understood as claiming the same in the broadest sense possible. Especially as to the 20 exhaust such a port opening is of the greatest importance, because it affords a quick escape for the hot compressed gases and allows the same to escape from the cylinder instantly. Furthermore, this quick escape 25 of the gases from the cylinder takes place from the lower as well as from the upper portion of the cylinder and does not cause the gases to pass upward from the piston, and thence outward through a port in the 30 upper portion of the cylinder, as has hitherto been necessary. Also the gases by their instant and free escape from the cylinder are quickly reduced to atmospheric pressure, and hence produce a very slight, if any, back 35 pressure on the piston and have a minimum heating effect during the exhaust.

My improved port opening is rendered progressively available or progressively unavailable by the piston as the latter moves 40 forward and backward respectively, that is, the port opening becomes increasingly available as the piston moves forward or outward, on the intake and explosion strokes, and becomes decreasingly available on the backward or inward scavenger strokes in the process of closing the exhaust and opening the inlet. By this means when the piston is near the outer or forward end of the cylinder, on the intake and explosion strokes, 45 leaving a large cylinder space to be filled or emptied, as the case may be, the port opening available in that position of the piston is correspondingly increased, and this effect is augmented by the lateral extensions of 50 the ports which I have already described. My improved port opening extending substantially the length of piston travel fills or empties the cylinder space behind the piston as rapidly as the piston moves, and 55 furthermore the gases enter or leave the cylinder transversely of the same behind the piston and do not have to deflect or bend as when the inlet and exhaust ports are near the inner end of the cylinder. Espe-

cially upon the intake through my improved 65 port means the charge does not have to enter at the rear or inner end of the cylinder and follow up the piston as the latter advances outward, which tends to retard admission and is a frequent cause of incomplete charging and inefficient action of the engine, but by my improved port opening the charge enters transversely into the cylinder directly behind the piston, wherever it is, and so there can be no failure to completely fill 75 the cylinder.

I desire it to be understood that I do not limit myself to the particular shape of either sleeve port or cylinder inlet and exhaust ports, which I have shown, nor indeed to any particular shape. The particular form of ports which I have shown and described for purposes of illustration are believed to be well adapted to the purpose, but there is no doubt that other shapes or 85 forms could be employed. Furthermore, it is not essential whether the ports be each a single opening or a plurality of adjacent openings. For instance, I have shown each port as having its extension which I have described separated from the main part of the port by a narrow bridge or strip of the metal which provides an unbroken portion of the surface of the member in which said port is formed. The bridge or strip is 95 thought to be desirable for the purpose of preventing the catching of piston rings and the like, and indeed it may be found necessary to have other bridges or strips lying across the ports so as to not make such a 100 large break in the contact surface of the member in which the port is formed. Such strips or divisions of the ports do not affect the broad idea of the invention, however, and theoretically each port might be a single 105 aperture or opening. Even with the particular forms of ports shown in the drawings it would be all right to make the cylinder ports include their extensions in one opening, but it will be noted that the form 110 of the sleeve port would have to be changed somewhat if the extension 22 were not separated by a dividing strip as shown, or it would overlap both the cylinder inlet and exhaust at the same time. From this it will 115 be seen that some advantage can be obtained in getting the maximum intake and exhaust by dividing the sleeve port into sections by the connecting strips referred to.

Wherever I have used the word "register" 120 herein, it is to be understood in the sense of coöperate, coact or overlie, as it is obvious from the ports which I have shown in the drawings that registration in the sense of exact coincidence of all edges simultaneously 125 is not meant and would be of no purpose.

The sleeve 11 may be provided with packing rings in any suitable manner to make it

4
tight, but I prefer to split the entire sleeve itself, as shown in Fig. 3, similar to the splitting of a piston ring, and thus make the sleeve its own packing ring. As shown in 5 said Fig. 3, the sleeve is preferably split upon an irregular line so as to provide tongues 36 and 37 interlocking with each other, and the ends of said tongues are of course beveled to overlap onto correspondingly beveled surfaces of the main portion of the sleeve, as is common in piston rings. When the sleeve is split, it is provided with a separate cylindrical driving portion 38, as shown in said Fig. 3, located below that part 10 of the cylinder which becomes most heated, although not so low that its joint with the split sleeve will ever be exposed by the cylinder. Said joint is by abutting ends of the sleeve and said cylindrical driving portion, one having recesses 39 adapted to receive 15 projections 40 upon the other, said projections being loose in said recesses, circumferentially. Obviously, the rear walls of the recesses will engage said projections and 20 turn the sleeve continuously without lost motion, while at the same time looseness of the projections in the recesses circumferentially allows for contraction or expansion of the sleeve, and thus prevents "seizing". 25 30 In this construction some means must be provided for holding the sleeve against longitudinal movement, such as the peripheral shoulder 41 on the outside of the sleeve engaging a similar shoulder 42 on the interior 35 of the cylinder. In case the upper and lower portions of the sleeve cannot separate longitudinally, as when the sleeve is in one piece, the bearings for the lower end of the sleeve which has the gear, are sufficient to 40 hold the sleeve against longitudinal movement.

In Fig. 6 I have shown a means for rotating the sleeve 11 consisting of a beveled gear 43 upon the crank shaft, meshing with 45 a coöperating beveled gear 44 upon a short shaft 45 journaled in suitable bearings upon the crank case and carrying at its opposite end the pinion 15. As already stated, however, I do not restrict myself to any particular form of drive.

When a number of cylinders are arranged together, as is usual in this type of engines, the various sleeves may be driven in any appropriate manner which imparts to them the proper relative positions, as may occur to anyone skilled in the art. It is possible, however, to arrange the cylinders as I have indicated in Fig. 7, with their sleeve gears 46, 47, 48 and 49 meshing one into another 55 in series, one end gear being driven by a pinion 50 corresponding to the pinion 15 already described. Obviously by this arrangement of sleeve gears, only alternate ones will move in the same direction, and adjacent

ones will move in opposite directions. This 65 can be accommodated, however, by making the two cylinders whose sleeves turn in opposite directions as a pair whose exhaust ports 51, and 52 may combine and whose inlet ports 53 and 54 may branch from a 70 common duct. The relative arrangement of inlet and exhaust ports according to my invention in fact favors the construction of such a pair of cylinders, as will be clear upon an examination of Fig. 7 of the drawings. 75

While I have described a rotary sleeve valve for controlling my improved port opening in conjunction with the piston, it will be understood that I do not restrict myself thereto and that any ordinary and well-known form of valve or other means adapted to and suitable for the purpose can be employed as may be desired by those skilled in the art. Furthermore, while I 80 have shown my invention applied to a four-cycle engine, I desire to be understood as contemplating its application to two-cycle or other types of engines and as covering 85 the invention herein regardless of the particular engine to which it may be applied. Various other modifications and deviations from that which is herein expressly shown for illustrative purposes may be made without departing from the spirit and scope of 90 the invention, and I do not wish to be understood as limiting myself except as required by the following claims when read in the light of the prior art.

Having thus described the invention, what 100 I claim is:

1. In an internal combustion engine, a piston, a cylinder having in its side wall a port opening extending substantially the 105 length of travel of said piston, a valve having a port adapted to coöperate with said cylinder port, and means for moving said valve so that its port will coöperate with said cylinder port while the piston is moving over it. 110

2. In an internal combustion engine, a piston, a cylinder having in its side wall a port opening extending substantially the 115 length of travel of said piston, a valve having a port adapted to coöperate with said cylinder port, and means for turning said valve so that its port will coöperate with said cylinder port while the piston is moving over it.

3. In an internal combustion engine, a 120 piston, a cylinder having in its side wall a port opening extending substantially the length of travel of said piston, a valve having a port adapted to coöperate with said cylinder port, and means for continuously 125 rotating said valve so that its port will coöperate with said cylinder port while the piston is moving over it.

4. In an internal combustion engine, a piston, a cylinder having in its side wall a port opening extending substantially the length of travel of said piston, a sleeve valve between said piston and cylinder having a port adapted to coöperate with said cylinder port, and means for moving said sleeve valve so that its port will coöperate with said cylinder port while the piston is moving over it. 65
5. In an internal combustion engine, a piston, a cylinder having in its side wall a port opening extending substantially the length of travel of said piston, a sleeve valve between said piston and cylinder having a port adapted to coöperate with said cylinder port, and means for moving said sleeve valve so that its port will coöperate with said cylinder port while the piston is moving over it. 70
- 15 6. In an internal combustion engine, a piston, a cylinder having in its side wall a port opening extending substantially the length of travel of said piston, a sleeve valve between said piston and cylinder having a port adapted to coöperate with said cylinder port, and means for moving said sleeve valve so that its port will coöperate with said cylinder port while the piston is moving over it. 75
- 20 7. In an internal combustion engine, a piston, a cylinder having in its side wall a port opening extending substantially the length of travel of said piston, a sleeve valve between said piston and cylinder having a port adapted to coöperate with said cylinder port, and means for continuously rotating said sleeve valve so that its port will coöperate with said cylinder port while the piston is moving over it. 80
- 25 8. In an internal combustion engine, a piston, a cylinder having in its side wall a port opening extending substantially the length of travel of said piston, a sleeve valve between said piston and cylinder having a port adapted to coöperate with said cylinder port, and means for continuously rotating said sleeve valve so that its port will coöperate with said cylinder port while the piston is moving over it. 85
- 30 9. In an internal combustion engine, a piston, a cylinder having in its side wall a port opening extending substantially the length of travel of said piston, a sleeve valve between said piston and cylinder having a port adapted to coöperate with said cylinder ports, and means for moving said sleeve so that its port will overlap said cylinder ports at such times that movement of the piston will close the inlet and open the exhaust. 90
- 35 10. In an internal combustion engine, a piston, a cylinder having in its side wall a port opening extending substantially the length of travel of said piston, a sleeve valve between said piston and cylinder having a port adapted to coöperate with said cylinder ports, and means for moving said sleeve so that its port will overlap said cylinder ports at such times that movement of the piston will close the inlet and open the exhaust. 95
- 40 11. In an internal combustion engine, a piston, a cylinder having in its side wall a port opening extending substantially the length of travel of said piston, a sleeve valve between said piston and cylinder having a port adapted to coöperate with said cylinder ports, and means for continuously rotating said sleeve so as to cause its port to coöperate with said cylinder ports alternately while the piston is moving over them. 100
12. In an internal combustion engine, a piston, a cylinder having in its side wall a port opening extending substantially the length of travel of said piston and having a lateral extension, a valve having a port adapted to coöperate with said cylinder port, and means for moving said valve so that its port will coöperate with said cylinder port while the piston is moving over it. 105
13. In an internal combustion engine, a piston, a cylinder having in its side wall a port opening extending substantially the length of travel of said piston and having a lateral extension at the outer or forward end of the cylinder, a valve having a port adapted to coöperate with said cylinder port, and means for moving said valve so that its port will coöperate with said cylinder port while the piston is moving over it. 110
14. In an internal combustion engine, a piston, a cylinder having in its side wall a port opening extending substantially the length of travel of said piston and having a lateral extension, a valve having a port with a lateral extension adapted to coöperate with said cylinder port, and means for moving said valve so that its port will coöperate with said cylinder port while the piston is moving over it. 115
15. In an internal combustion engine, a piston, a cylinder for said piston having elongated lateral inlet and exhaust ports extending longitudinally of the cylinder for nearly the length of the stroke of said piston, a sleeve valve having a port adapted to register with said cylinder ports, and means for turning said sleeve to bring its port successively into and out of registration with said cylinder ports in turn. 120
16. In an internal combustion engine, a piston, a cylinder for said piston having elongated lateral inlet and exhaust ports extending longitudinally of the cylinder for nearly the length of the stroke of said piston, a sleeve valve having a port adapted to register with said cylinder ports, and 125

means for rotating said sleeve continuously in one direction to cause its port to coöperate with the cylinder ports in turn.

17. In an internal combustion engine, a piston, a cylinder for said piston having elongated lateral inlet and exhaust ports extending longitudinally of the cylinder nearly the length of the stroke of said piston, a sleeve valve having a port adapted 10 to register with said cylinder ports, and means for turning said sleeve at a slower speed than that of the piston, said sleeve and the piston operating in conjunction with each other to vary the intake and exhaust openings.

18. In an internal combustion engine, a piston, a cylinder for said piston having elongated lateral inlet and exhaust ports extending longitudinally of the cylinder 20 for nearly the length of the stroke of said piston, a sleeve valve having a port adapted to register with said cylinder ports, and means for rotating said sleeve continuously in one direction at a slower speed than that 25 of the piston, said sleeve and the piston adapted to coöperate in varying the intake and exhaust openings.

19. In an internal combustion engine, a cylinder having an inlet port and an exhaust port in its side wall, a sleeve valve having a port adapted to register with said cylinder ports, all said ports having extensions the sleeve port extension adapted to register with the inlet port extension at 30 the end of the intake and with the exhaust port extension at the beginning of the exhaust, means for moving said sleeve to bring its port successively into and out of registration with said cylinder ports in turn, 35 and a piston adapted to operate in conjunction with said sleeve to vary the intake and exhaust openings.

20. In an internal combustion engine, a cylinder having an inlet port and an exhaust port in its side wall, a sleeve valve having a port adapted to register with said cylinder ports, all said ports having extensions the sleeve port extension adapted to register with the inlet port extension at 40 the end of the intake and the exhaust port extension at the beginning of the exhaust, means for turning said sleeve to bring its port successively into and out of registration with said cylinder ports in turn, and a piston adapted to operate in conjunction with said sleeve to vary the intake and exhaust openings.

21. In an internal combustion engine, a cylinder having an inlet port and an exhaust port in its side wall, said ports having extensions directed toward each other, a sleeve valve having a port adapted to register with said cylinder ports, said sleeve port having an extension adapted to regis- 60

ter with the said extensions of the cylinder 65 ports in turn, means for rotating said sleeve continuously in one direction to cause its port to register with the cylinder ports in turn and its extension to register with the inlet port extension at the end of the intake 70 and with the exhaust port at the beginning of the exhaust, and a piston adapted to operate in conjunction with said sleeve to vary the intake and exhaust openings.

22. In an internal combustion engine, a cylinder having lateral inlet and exhaust ports arranged longitudinally of the cylinder, said ports having next the outer end of the cylinder lateral extensions directed toward each other, a sleeve valve having a port adapted to register with said cylinder 75 ports, said sleeve port having an extension adapted to register with the said extensions of the cylinder ports in turn, means for turning said sleeve, and a piston adapted to operate in conjunction with said sleeve to open the inlet port extension at the end of the intake and to open the exhaust port extension at the beginning of the exhaust.

23. In an internal combustion engine, a cylinder having lateral inlet and exhaust ports arranged longitudinally of the cylinder, said ports having next the outer end of the cylinder lateral extensions directed toward each other, a sleeve valve having a port adapted to register with said cylinder 90 ports, said sleeve port having an extension adapted to register with the said extensions of the cylinder ports in turn, means for rotating said sleeve continuously in one direction, and a piston adapted to operate in conjunction with said sleeve to open the inlet port extension at the end of the intake and to open the exhaust port extension at the beginning of the exhaust.

24. In an internal combustion engine, a piston, a cylinder for said piston having lateral inlet and exhaust ports extending longitudinally of the cylinder nearly the length of the stroke of said piston, said ports having next the outer end of the cylinder lateral extensions directed toward each other, a sleeve valve having a port adapted to register with said cylinder 95 ports, said sleeve port having an extension adapted to register with the said extensions of the cylinder ports in turn, and means for turning said sleeve.

25. In an internal combustion engine, a piston, a cylinder for said piston having lateral inlet and exhaust ports extending longitudinally of the cylinder for nearly the length of the stroke of said piston, said ports having next the outer end of the cylinder lateral extensions directed toward each other, a sleeve valve having a port adapted to register with said cylinder ports, said sleeve port having an extension adapted to register with the said extensions of the cyl- 100 110 115 120 125

inder ports, and means for rotating said sleeve continuously in one direction to bring its said port extension into registration with the cylinder inlet extension at the end of the intake and into registration with the cylinder exhaust port at the beginning of the exhaust.

26. In an internal combustion engine, a cylinder having an inlet port and an exhaust port circumferentially arranged in its side wall, a piston in said cylinder, a sleeve valve having a port adapted to register with a port of said cylinder, said sleeve valve being split longitudinally and having at its edges intermeshing overlapping tongues, and means for operating said sleeve valve to move its port into and out of registration with said cylinder port.

27. In an internal combustion engine, a cylinder having an inlet port and an exhaust port circumferentially arranged in its side wall, a piston in said cylinder, a sleeve between said piston and cylinder having a port adapted to register with a port of the cylinder, said sleeve being split longitudinally and having at its edges overlapping tongues, and means for operating said sleeve valve to move the port into and out of registration with the cylinder port.

28. In an internal combustion engine, a cylinder having a port in its side wall, a piston for said cylinder, a sleeve valve having an upper split portion with a port adapted to register with the port of the cylinder and a lower annular portion, said portions having in their adjacent end edges one recesses and the other projections extending into said recesses, and means for turning said lower portion.

29. The combination with the cylinder and piston of an explosive engine, of a valve mechanism for controlling admission and exhaust, said cylinder having in one wall a port extending from a point inward nearly as far as the point reached by the inner end of the piston on its extreme inward movement, outward as far as a point reached by the inner end of the piston on its outward movement at the time said port is open to exhaust.

30. The combination with the cylinder and piston of an explosive engine, said cylinder having in one wall a port extending approximately the full length of the piston movement, of a valve operating to open and close said port with a properly timed action.

31. In an explosive engine, a cylinder having a port extending approximately the full length of the piston movement, and a valve coöperating with said cylinder port to open and close the same with a properly timed action.

32. In an explosive engine, the combination with a cylinder having a port extended

longitudinally thereof approximately the full length of the piston movement, but terminating short of the extreme inward position of said piston, whereby said port will be closed by said piston at the time of explosion, and a valve coöperating with said cylinder port to open and close the same with a properly timed action.

33. The combination with a cylinder and piston of an explosive engine, of a rotary controlling valve controlling admission and exhaust, said cylinder having a port controlled by said valve and which port is extended from a point inward nearly as far as the point reached by the inner end of the piston on its inward movement, outward as far as the point reached by the inner end of the piston at the time the said port is open to exhaust by the said valve, and means for rotating said valve with a properly timed action in respect to said piston.

34. An internal combustion engine having a cylinder, a piston, an exhaust port opening in said cylinder extending for substantially the distance of piston travel and adapted to be rendered decreasingly available on backward movement of the piston, and means apart from said piston for opening and closing said port opening.

35. An internal combustion engine having a cylinder, a piston, port means extending substantially the length of piston travel and adapted to be rendered progressively available or unavailable on piston movement, and means comprising a slide valve for uncovering said port means on one stroke of the piston, while maintaining the same covered during the succeeding strokes thereof.

36. An internal combustion engine having a cylinder with a port opening extending substantially the distance of piston travel, and means for opening and closing said port opening with a properly timed action.

37. An internal combustion engine having a piston, a cylinder with a port opening extending substantially the distance of piston travel, and valve means adapted to coöperate with said piston in opening and closing said port with a properly timed action.

38. An internal combustion engine having a piston, a cylinder with an exhaust port extending substantially the length of piston travel and adapted to be rendered increasingly available on forward movement of the piston, and means other than the piston for opening said port on each alternate forward stroke of the piston and succeeding inward stroke and for closing said port on the other forward and rearward strokes.

39. An internal combustion engine having a piston, a cylinder with a port opening extending substantially the distance of piston travel and adapted to be rendered progressively available or unavailable by piston

movement, and means other than said piston for opening and closing said port opening.

40. An internal combustion engine having a piston, a cylinder with an inlet port extending substantially the distance of piston travel and adapted to be rendered increasingly available by piston movement, and means other than said piston for opening and closing said inlet port.

10 41. An internal combustion engine having a piston, a cylinder with an inlet port extending substantially the length of piston travel and adapted to be rendered increasingly available on forward movement of the 15 piston, and means other than the piston for opening said port on each alternate forward stroke of the piston and for closing said port on the other forward strokes and all the reverse strokes.

20 42. An internal combustion engine having a cylinder, a piston, admission port means and exhaust port means in said cylinder both extending substantially the length of piston travel and adapted to be rendered progressively available or unavailable by movement of the piston, and means other than the piston for uncovering said exhaust port means on one rearward stroke of the piston and for uncovering said admission 30 port means on the next succeeding forward stroke of the piston and for maintaining both said port means closed on the next succeeding rearward and forward piston strokes.

35 43. An internal combustion engine having a cylinder, a piston, a prolonged port opening in the cylinder extending for a substantial part of the distance of piston travel, a rotary valve sleeve interposed between the 40 piston and the cylinder and having a valve port adapted to register with the port opening in said cylinder, said valve port being adapted to be rendered progressively available by piston movement and so positioned 45 as to be covered by the piston in the rearward position of the latter, and means to rotate said valve.

44. An internal combustion engine having a cylinder, a piston, an admission port and an exhaust port in said cylinder, both extending approximately the length of the piston stroke, a rotary sleeve valve interposed between said piston and said cylinder and having port means adapted to register with said admission and exhaust ports, said cylinder port means being rendered progressively available by movement of the piston 55 and being covered by the piston in its rearward position on compression and firing, and means to rotate the valve.

45. In an explosive engine, a cylinder having a port extending approximately the full length of the piston movement, and a controlling valve moved with a properly timed

action and provided with a port co-operating with said cylinder port to simultaneously open said cylinder port from end to end.

46. In an explosive engine, the combination with a cylinder having in one wall a longitudinal port extending approximately the full length of the piston movement, of a valve extended longitudinally of said cylinder adjacent to the port in the wall thereof and co-operating with said port and operating under its initial movement to open said cylinder port from end to end in the exhaust action.

47. The combination with the cylinder and piston of an explosive engine, said cylinder having a longitudinal port extending approximately the full length of the piston movement but terminating slightly short of the extreme innermost position of said piston, whereby said cylinder port will be closed by said piston at the time of explosion, and a rotary valve having a port co-operating with said cylinder port with a properly timed action.

48. The combination with a cylinder and piston of an explosive engine, of a valve mechanism for controlling admission and exhaust, said cylinder having in one wall a port extending from a point inward nearly as far as the point reached by the inner end of the piston on its extreme inward movement and outward as far as a point reached by the inner end of the piston on its outward movement at the time said port is open to exhaust.

49. The combination with a cylinder and piston of an explosive engine, of a rotary controlling valve extending longitudinally of and seated adjacent to one wall of said cylinder and controlling admission and exhaust, said cylinder and valve having co-operating ports that extend from a point inward nearly as far as the point reached by the inner end of a piston on its inward movement and outward as far as the point reached by the inner end of said piston on its outward stroke at the time said ports are open to exhaust by said valve.

50. An internal combustion engine including a cylinder with exhaust and inlet ports having a length nearly equal to the full length of the cylinder, and a valve coacting with a cylinder and having a port extending nearly the full length of the cylinder and adapted to register with the ports in the cylinder.

51. An internal combustion engine including a cylinder having inlet and exhaust ports extending longitudinally of the cylinder nearly the entire length thereof, said ports being separated from each other and each of said ports being bridged by a strengthening web, and a valve having a

- port adapted to register with the inlet and exhaust ports of the engine and extending longitudinally of the valve sleeve nearly its entire length.
5. 52. The combination with the cylinder and piston of an explosive engine, said cylinder having in one wall a port extending approximately the full length of the piston movement, of a valve extended longitudinally of said cylinder and seated adjacent to one wall thereof and having a port co-operating with the said port in said cylinder. 65
10. 53. The combination with the cylinder and piston of an explosive engine, of a rotary controlling valve extended longitudinally of and seated adjacent to one wall of said cylinder, said cylinder and valve having co-operating ports that extend approximately the full length of the stroke of said piston, and means for rotating said valve with a properly timed action in respect to the movements of said piston. 70
15. 54. In an internal combustion engine, a piston, a cylinder having in its side wall a port opening extending substantially the length of travel of said piston and having a lateral extension at the outer or forward end of the cylinder, a valve having a port with a lateral extension at the outer or forward end of the cylinder adapted to co-operate with said cylinder port, and means for moving said valve so that its port will co-operate with said cylinder port while the piston is moving over it. 75
20. 55. In an internal combustion engine, a piston, a cylinder having in its side wall inlet and exhaust ports extending substantially the length of travel of said piston and having lateral extensions extending toward each other, a valve having a port adapted to co-operate with said cylinder ports, and means for moving said valve so that its port will co-operate with said cylinder ports alternately while the piston is moving. 80
25. 56. In an internal combustion engine, a piston, a cylinder having in its side wall inlet and exhaust ports extending substantially the length of travel of said piston and having lateral extensions extending toward each other at the forward or outer end of the cylinder, a valve having a port adapted to co-operate with said cylinder ports, and means for moving said valve so that its port will co-operate with said cylinder ports alternately while the piston is moving over them. 85
30. 57. In an internal combustion engine, a piston, a cylinder having in its side wall a port opening extending substantially the length of travel of said piston and having a lateral extension at the outer or forward end of the cylinder, said cylinder having a bridge across said port opening adjacent said lateral extension, a valve having a port adapted to co-operate with said cylinder port, and means for moving said valve so that its port will co-operate with said cylinder port while the piston is moving over it. 90
35. 58. In an internal combustion engine, a piston, a cylinder having in its side wall a port opening extending substantially the length of travel of said piston and having a lateral extension at the forward or outer end of the cylinder adapted to co-operate with said cylinder ports, and means for moving said valve so that its port will co-operate with said cylinder ports alternately while the piston is moving over them. 95
40. 59. In an internal combustion engine, a piston, a cylinder having in its side wall a port opening extending substantially the length of travel of said piston and having a lateral extension, said cylinder having a bridge across said port opening adjacent said lateral extension, a valve having a port adapted to co-operate with said cylinder port, and means for moving said valve so that its port will co-operate with said cylinder port while the piston is moving over it. 100
45. 60. In an internal combustion engine, a piston, a cylinder having in its side wall a port opening extending substantially the length of travel of said piston and having a lateral extension at the outer or forward end of the cylinder, said cylinder having a bridge across said port opening adjacent said lateral extension, a valve having a port adapted to co-operate with said cylinder port, and means for moving said valve so that its port will co-operate with said cylinder port while the piston is moving over it. 105
50. 61. In an internal combustion engine, a piston, a cylinder having in its side wall a port opening extending substantially the length of travel of said piston and having a lateral extension, said cylinder having a bridge across said port opening adjacent said lateral extension, a valve having a port with a lateral extension adapted to co-operate with said cylinder port and having a bridge across said port adjacent said lateral extension, and means for moving said valve so that its port will co-operate with said cylinder port while the piston is moving over it. 110
55. 62. In an internal combustion engine, a piston, a cylinder having in its side wall a port opening extending substantially the length of travel of said piston and having a lateral extension at the outer or forward end of the cylinder, said cylinder having a bridge across said port opening adjacent said lateral extension, a valve having a port with a lateral extension at the outer or forward end of the cylinder adapted to co-operate with said cylinder port, and means for moving said valve so that its port will co-operate with said cylinder port while the piston is moving over it. 115
60. 63. In an internal combustion engine, a piston, a cylinder having in its side wall a port opening extending substantially the length of travel of said piston and having a lateral extension, said cylinder having a bridge across said port opening adjacent said lateral extension, a valve having a port with a lateral extension at the outer or forward end of the cylinder adapted to co-operate with said cylinder port, and means for moving said valve so that its port will co-operate with said cylinder port while the piston is moving over it. 120
65. 64. In an internal combustion engine, a piston, a cylinder having in its side wall a port opening extending substantially the length of travel of said piston and having a lateral extension at the outer or forward end of the cylinder, said cylinder having a bridge across said port opening adjacent said lateral extension, a valve having a port with a lateral extension at the outer or forward end of the cylinder adapted to co-operate with said cylinder port, and means for moving said valve so that its port will co-operate with said cylinder port while the piston is moving over it. 125

- erate with said cylinder port, and means for moving said valve so that its port will co-operate with said cylinder port while the piston is moving over it.
63. In an internal combustion engine, a piston, a cylinder having in its side wall a port opening extending substantially the length of travel of said piston and having a lateral extension at the outer or forward end of the cylinder, said cylinder having a bridge across said port opening, adjacent said lateral extension, a valve having a port with a lateral extension at the outer or forward end of the cylinder adapted to co-operate with said cylinder port and having a bridge across said port adjacent said lateral extension, and means for moving said valve so that its port will co-operate with said cylinder port while the piston is moving over it. 65
64. In an internal combustion engine, a piston, a cylinder having in its side wall inlet and exhaust ports extending substantially the length of travel of said piston and having lateral extensions extending toward each other, said cylinder having bridges across said ports adjacent their said lateral extensions, a valve having a port adapted to co-operate with said cylinder ports, and means for moving said valve so that its port will co-operate with said cylinder ports alternately while the piston is moving. 70
65. In an internal combustion engine, a piston, a cylinder having in its side wall inlet and exhaust ports extending substantially the length of travel of said piston and having lateral extensions extending toward each other at the forward or outer end of the cylinder, said cylinder having bridges across said ports adjacent their said lateral extensions, a valve having a port adapted to co-operate with said cylinder ports, and means for moving said valve so that its port will co-operate with said cylinder ports alternately while the piston is moving over them. 75
66. In an internal combustion engine, a piston, a cylinder having in its side wall longitudinal inlet and exhaust ports with lateral extensions extending toward each other, said cylinder having bridges across said ports adjacent their said lateral extensions, a valve having a port with a lateral extension adapted to co-operate with said cylinder ports, and means for moving said valve so that its port will co-operate with said cylinder ports alternately while the piston is moving over them. 80
67. In an internal combustion engine, a piston, a cylinder having in its side wall longitudinal inlet and exhaust ports with lateral extensions extending toward each other, said cylinder having bridges across said ports adjacent their said lateral extensions, a valve having a port with a lateral 85
- extension adapted to co-operate with said cylinder ports and having a bridge across said port adjacent said lateral extension, and means for moving said valve so that its port will co-operate with said cylinder ports alternately while the piston is moving over them. 90
68. In an internal combustion engine, a piston, a cylinder having in its side wall longitudinal inlet and exhaust ports with lateral extensions extending toward each other at the forward or outer end of the cylinder, said cylinder having bridges across said ports adjacent their said lateral extensions, a valve having a port with a lateral extension at the forward or outer end of the cylinder adapted to co-operate with said cylinder ports, and means for moving said valve so that its port will co-operate with said cylinder ports alternately while the piston is moving over them. 95
69. In an internal combustion engine, a piston, a cylinder having in its side wall longitudinal inlet and exhaust ports with lateral extensions extending toward each other at the forward or outer end of the cylinder, said cylinder having bridges across said ports adjacent their said lateral extensions, a valve having a port with a lateral extension at the forward or outer end of the cylinder adapted to co-operate with said cylinder ports and having a bridge across said port adjacent said lateral extension, and means for moving said valve so that its port will co-operate with said cylinder ports alternately while the piston is moving over them. 100
70. In an internal combustion engine, a cylinder having a port in its side wall, a piston for said cylinder, a sleeve valve between said piston and cylinder having an upper portion with a port adapted to co-operate with the port of the cylinder and a lower annular portion, said portions having in their adjacent end edges one recesses and the other projections extending into said recesses, and means for turning said lower annular portion. 105
71. In an internal combustion engine, a cylinder having a port in its side wall, a piston for said cylinder, a sleeve valve between said piston and cylinder having an upper portion with a port adapted to co-operate with the port of the cylinder and a lower annular portion, said portions having in their adjacent end edges one recesses and the other projections extending into said recesses, means for preventing longitudinal motion of said upper and lower valve portions, and means for turning said lower annular portion. 115
72. In an internal combustion engine, a cylinder having a port in its side wall, a piston for said cylinder, a sleeve valve between said piston and cylinder having an upper portion with a port adapted to co- 120

operate with the port of the cylinder and a lower annular portion, said portions having in their adjacent end edges one recesses and the other projections extending loosely 5 into said recesses, and means for turning said lower annular portion.

73. In an internal combustion engine, a cylinder, a piston, a sleeve valve between said piston and cylinder split longitudinally

and having at the adjacent edges formed 10 thereby tongues interlocking so as to close the split against the longitudinal passage of gas, and means for turning said sleeve valve.
